James D. Sparkman, (Williamsburgh) & Melville Kelsey, (Brooklyn, N. Y.)
Letters Patent (Design No. 76) dated 25 July 1846. ante dated
29th March 1846

The Schedule referred to in these Letters Patent and making
part of the same.

To all unto whom these presents ~~shall~~ ^{may} come:

Know Ye, that Mr. James D. Sparkman, of Williamsburgh, and Melville Kelsey, of
the City of Brooklyn, both in the County of Kings, and State of New York, Manufacturer-
ers, have invented, arranged, produced and applied to use, a new original and ornamental
Design, presenting the appearance of Mosaic and Fretwork, combined in a Gothic charac-
ter, and originally intended for, and applied in the printing of fabrics, which when so
printed, are termed "floor oil cloths" but which design can be wrought in, or on, any
material by any of the existing well-known means of applying materials, of diffe-
rent colors and textures, to produce a required figured surface for any required
use for which new original and ornamental Design, we seek Letters Patent
of the United States, irrespective of the mechanical means, by which the design
may be formed, and irrespective of the colors, or materials, employed in produ-
cing the configuration of the Design itself, which in the present case, we design-
name as our "Gothic Pavement Pattern Design," and which design is fully and
artistically represented in the Drawing, annexed to, and making a part of this
~~description~~ ^{we} specification thereof. In this a square A, is set diagonally with
the length of the fabric worked on, and has a border of about one quarter the
linear measure of the square, the border mitred at the angles, and the points
of meeting, at the angles of each four squares, finished and interlocked by a

heart-leaved rosette a; midway in the borders, a fancy figure b is placed and finishes uniform each way from the centre. In the centre space c, is an uniform fancy figure, having on each end, a triplicated Maltese cross d, and in the centre, a four folded short quadruplicated Maltese cross e, the bases of the four crosses standing together, and the central ornamental figures, thus made, have alternations of light central ground, with dark concentric fancy figures, and vice versa, or dark grounds, and light figures, the parts of this design can hardly be described, by any known artistic, or technical terms, but the parts, identified by letters in the drawing, and the filling up of the other parts, will show what we have designed, and claim as new, and desire to secure by Letters Patent of the United States, namely, the arrangement and application, and especial disposition of the parts, to produce the ultimate configuration and design, as represented in the drawing, irrespective of the mechanical means by which the Figure is produced, and irrespective of the materials, and colors, employed in conjunction with each other for the purpose of producing the said figure and design.

In witness whereof we have hereunto set our hands and seals in the City of New York, this fourteenth day of July One thousand eight hundred and forty six.

Witness,

W. Sennell

Samuel H. Sennell

James D. Starkman Melville Kelsey. 644 w 07
